US0D1096612S

(12) **United States Design Patent** (10) **Patent No.:** **US D1,096,612 S**
(45) **Date of Patent:** **** Oct. 7, 2025**

(54) **VEHICLE BATTERY**

(71) Applicants: **CPS Technology Holdings LLC**, New York, NY (US); **Clarios Advanced Solutions GmbH**, Hannover (DE)

(72) Inventors: **Nicholas E. Elison**, Mequon, WI (US); **Jeffrey Michael Watts**, Milwaukee, WI (US); **Christopher M. Bonin**, South Milwaukee, WI (US); **Marco Jansen**, Lower Saxony (DE); **Joerg Birkholz**, Lower Saxony (DE); **Ethan Michael Corr**, Milwaukee, WI (US)

(73) Assignees: **CPS Technology Holdings LLC**, New York, NY (US); **Clarios Germany GmbH & Co. KG**, Hannover (DE)

(**) Term: **15 Years**

(21) Appl. No.: **29/872,197**

(22) Filed: **Mar. 8, 2023**

(57) **CLAIM**

The ornamental design for a vehicle battery as shown.

DESCRIPTION

FIG. 1 is a front perspective view of a vehicle battery;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines in the drawing are for the purpose of illustrating portions of the vehicle battery and form no part of the claimed design.

1 Claim, 7 Drawing Sheets
